UNITED STATES PATENT OFFICE.

RUPERT BREYLEY, OF PAINESVILLE, OHIO.

CAR STOP.

Application filed April 1, 1925. Serial No. 19,734.

To all whom it may concern:

Be it known that I, RUPERT BREYLEY, a citizen of the United States, residing at Painesville, in the county of Lake and State 5 of Ohio, have invented a certain new and useful Improvement in Car Stops, of which the following is a full, clear, and exact description, reference being had to the accompanying drawings.

This invention relates to that class of devices known as friction car stops which comprise shoes carried by the opposed rails of a track and slidable from a normal position thereon to a second position, the shoes 15 carrying the advancing wheels of the rolling stock and sliding under the weight of their burden along the rails until the friction between the shoes and rails overcomes the momentum of the rolling stock, or until 20 the shoes come in contact with abutments, or until the rolling stock engages a bumper. Upon subsequent movement of the rolling stock in the opposite direction, the shoes are 25 returned by the wheels to normal position wherein they are stopped by suitable obstructions, usually fish plates which connect adjoining rails.

With a view of eliminating the faults possessed by prevailing car stops of the 30 above mentioned class, my invention comprehends the following principal objects:

To provide a friction car stop that is 35 equally suitable for use independently of, or in conjunction with, a stationary bumper 40 of a type wherein the bolster is sustained by structural members that are fastened directly to the track rails, the car stop being so designed as to escape obstructions situated along the rails and common to the aforesaid type of bumper;

To provide a friction car stop which, when used alone or with a stationary bumper, causes no loss of track space;

To provide a friction car stop wherein the 45 shoes are returned to normal position by the revolving wheels of the rolling stock and without appreciable friction;

To provide a shoe for friction car stops 50 which is of unique design, being preferably formed as an integral casting, and wherein the pull-back is spaced from the wheel obstructing portion so that as the advancing wheels enter the stop they ride over the pull-backs of the opposed shoes and drop 55 directly onto the rails, thereby preventing

distortion of the shoes through continued use and insuring throughout the life of the stop a flat bearing surface of the shoes upon the rails at all points throughout their lengths;

To provide a shoe for friction car stops which as above mentioned is preferably formed as an integral casting and having that portion which frictionally engages the rails of a softer quality of metal than that portion of its pull-back which is engaged by the wheel during the return of the stop to normal position thereby to acquire the maximum efficiency during the stopping of the rolling stock and to render as easy as 70 possible the return of the stop to normal position; and

To provide a friction car stop which, by suitable rigging, may be shifted with respect to the rolling stock sufficiently to disengage the pull-backs of the opposed shoes from the wheels wherewith they normally engage during the return movement of the stop so that the manual operation of shifting the car along the track, commonly known as "pinching a car," may be as easily performed as under ordinary circumstances.

Further and more general objects are to provide a highly efficient car stop that is particularly convenient of installation, is 85 very durable, and is comprised of few parts that are cheap of manufacture and easy of assembly.

The foregoing objects, with others herein-after appearing, are attained in the construction illustrated in the accompanying drawings wherein Fig. 1 is a side elevation of my improved car stop mounted upon a track; Fig. 2 is a fragmentary plan view of the stop; Figs. 3, 4 and 5 are sectional details on the lines 3-3, 4-4 and 5-5, respectively, of Fig. 1; Fig. 6 shows a section of track in side elevation at the right hand end of which is situated a stationary car bumper and at the left hand end of which is shown in normal position my improved friction car stop; Fig. 7 is a view, similar to Fig. 6, showing a car engaging the stationary bumper with the wheels of the advancing truck resting upon the friction car stop; Fig. 8 shows the car proceeding away from the stationary bumper and returning the friction stop to normal position; Fig. 9 is a sectional view taken longitudinally of the track and showing the friction car stop 110

so adjusted with respect to the car that the car may be shifted along the track in the direction indicated by the arrow with the customary ease; Fig. 10 is a fragmentary plan view of what is shown in Fig. 9; and Fig. 11 is a sectional detail of one of the abutments wherewith, under certain conditions, the friction car stop engages, the section being taken on the line 11-11 of Fig. 6.

10 The friction car stop is comprised of right and left hand shoes, each being preferably formed of an integral casting. Each shoe includes a comparatively long rail-engaging section 1, the upper surface of which, adjacent its forward end, merges into an upwardly inclined curved wheel obstructing portion 2. The upper end of this portion is joined to the forward extremity of the section 1 by a brace 3. The top surface of 15 the section 1, at its rear end, is gradually inclined downwardly, as shown at 4, to the top surface of the rail A. Spaced longitudinally of the rail a suitable distance from the section 1 is a part which I shall term 20 the pull-back 5. This has a bearing upon the ball of the rail of considerable extent and it gradually tapers from a relatively thin edge at the rear end of the shoe to a suitable elevation where it joins, through a 25 horizontal surface 6, a downwardly curved portion 7 that descends to the top surface of the rail. Consequently between the parts designated 4 and 7 the wheel engaging surface of the rail is exposed. The pull-back 30 5 is connected to the section 1 by means of a laterally disposed angular beam 8 shown in cross section in Fig. 4. On opposite sides of the pull-back 5, and at about the rear end of beam 8, are lugs 10 which extend down 35 along side and beneath the ball of the rail into close proximity to the web thereof, as shown in detail in Fig. 3. At the forward extremity of the shoe, the section 1 is formed with lugs 11 which embrace the ball of the 40 rail but do not extend below the same. The formation of these lugs is best illustrated in the sectional detail of Fig. 5. Smaller lugs 12 are formed on opposite sides of the section 1 a suitable distance rearwardly of the lugs 11. The lugs 12, like those just described, are no deeper than the ball of the rail. The upper ends of the portions 2 of the opposed shoes are tied together by a rod or bolt 13, and are maintained a fixed distance apart by a tubular spacer 14 that is 45 applied to the bolt or rod.

Considering the device as though used independently of a stationary bumper, abutments 15 (Figs. 6, 7, 8 and 11) are secured, as by bolts 16, to the rails A at a point where it is desired to bring the car to a stop. In entering the stop, the front wheels of the advancing truck ride over the pull-backs 5 and drop directly upon the rails from whence they pass up the inclined portions

4 onto the sections 1 and travel therealong until stopped by the portions 2. When the front wheels have acquired this position, the rear wheels of the truck are resting upon the longer inclines of the pull-backs 5, as 70 shown in Fig. 7. Under the weight of its load, and the influence of the load's momentum, the car stop slides along the track until the friction between the shoes and the rails overcome the momentum, or until the 75 lugs 11 engage the abutments 15 (it being remembered that we are now considering the operation of the car stop as though the stationary bumper were not present).

There is, however, a peculiar advantage in 80 the conjoint use of a friction car stop and a stationary bumper. In Figs. 6, 7 and 8 I have shown a highly desirable type of bumper, designated B, and comprising a bolster b that is sustained at an elevation to 85 receive the bumper engaging part c of a car C by struts b' and tension member b² which may be constituted of rails having horizontal portions b³ that lie on the ties (not shown) along side the rails A and are fastened to said rails by bolts b⁴ and spaced therefrom by stringers b⁵ through which, and the rails and tension members b², the bolts b⁴ pass. This is standard construction. The lugs 11 and 12 of the shoes are 90 made short, as above described, so as to avoid interference with the stringers b⁵, thus allowing the shoes to pass along side the tension members b² and the car to engage the bumper B. I am permitted to shorten 95 the lugs 11 and 12 in the manner stated because they have only the one function of maintaining the shoes against lateral displacement. Were it necessary, as in prior 100 types of friction car stop wherewith I am familiar, to engage the lugs at the forward ends of the shoes beneath the balls of the rails, it would not be possible to use the stop in conjunction with bumpers of the type above described.

105 The difference between my improved bumper and the prior ones referred to and which difference is responsible for this modification of the lugs and the benefits arising therefrom, is the space between the pull-back 115 5 and the section 1 of each shoe. Without such a space, the continual hammering of the wheels upon the comparatively thin portions of the shoes, as said wheels drop from the pull-backs when entering the stop, would 120 be liable to cause a displacement of the metal that would result in the shoes assuming a rocker shape, and if such a condition should develop and the lugs were short they would 125 soon rise so high with respect to the rails that they would be of no effect.

130 In the bumper installation, as above described and as illustrated in Figs. 6, 7 and 8, the abutments 15 are employed merely as a safeguard in case the bumper fails. They

are placed beyond the limit of normal advance movement of the friction car stop as will be seen by reference to Fig. 7.

If the rolling stock is to be stopped by engagement with a fixed obstruction, rather than solely through the action of the friction car stop, it is better that the suspended load engage the obstruction, than the trucks from which the load is suspended. This is for the obvious reason that by far the greater part of the momentum is in the suspended load. In the bumper installation, the friction car stop serves to retard the movement of the rolling stock, while the bumper serves to positively arrest the movement of the load thus avoiding strains which would otherwise occur in the car structure between the body and the truck.

When the rolling stock is moved in the direction indicated by the arrow in Fig. 8, the wheels previously described as the rear wheels of the truck ride off the pull-backs 5 and the front wheels withdraw from the portions 1 and bear upon the rails through the spaces between said portions and the pull-backs. As the car continues in the aforesaid direction said wheels engage the upper ends of the inclined portions 7 (as indicated in Fig. 1 where the tread of the wheel is represented by the broken line x) and shove the stop along the track until the lugs 10 engage the fish plates a . These fish plates arrest movement of the car stop and the car wheels ride over the pull-backs 5, leaving the stop in normal position for its next operation. It may be explained in this connection that the portion of each pull-back, engaged by the car wheel during the return movement of the stop, is hardened, as represented by the shading in Fig. 1, for the double purpose of preventing undue wear of the shoe and for reducing the friction between it and the wheel. The rail engaging portions of the shoe are left as soft as practical so as to increase the friction between the shoe and the rail when the shoe is being slid forwardly under load.

It frequently becomes necessary to shift cars along a track by manual power, an operation commonly referred to as "pinching" a car. This is done by means of a crow-bar like implement, called a "pinch bar," which is adapted to be wedged between the rail and a wheel of the car and alternately raised and lowered. A man is indicated in dotted lines in Fig. 9 in the act of pinching the car in a direction indicated by the arrow appearing on the car in this view. In order to avoid interference with this operation by the friction car stop the same is shifted with respect to the car by suitable rigging. In Figs. 9 and 10 this rigging is shown as comprised of a Y-shaped yoke 16 that is engaged with the car stop and has pivoted to the end of its stem a cam lever 17 which is

adapted to be engaged through the terminal link of a chain 18 that is connected by a hook 19 to the car axle 20. When the lever 17 is engaged through said link and is swung to the position shown in the drawing, in which position it may be held by a ring 21, it advances the car stop with respect to the car enough to withdraw the pull-backs from the wheels. The car may now be moved forwardly with comparative ease, the car stop sliding freely along the track during the operation.

Having thus described my invention, what I claim is:

1. A shoe for a friction car stop adapted to be slidably mounted on a rail and comprising two wheel carrying parts that are spaced apart so as to expose between them a section of the wheel engaging surface of the rail, one of said parts including a wheel obstructing portion and the other constituting a pull-back, and means spaced laterally of the rail for tying said parts together. 80

2. A shoe for a friction car stop adapted to be slidably mounted on a rail, said shoe consisting of an integral casting comprised of two wheel carrying parts that are spaced apart so as to expose between them a section of the wheel engaging surface of the rail, one of said parts including a wheel obstructing portion and the other constituting a pull-back, and a beam disposed laterally of the rail and tying the aforesaid parts together. 90

3. A shoe for a friction car stop adapted to be slidably mounted on a rail and comprising two wheel carrying parts that are spaced apart so as to expose between them a section of the wheel engaging surface of the rail, the first of said parts including a wheel obstructing portion and the second constituting a pull-back, means disposed laterally of the rail for tying said parts together, lugs depending from opposite sides of the pull-back and extending beneath the ball of the rail, and means for maintaining the first of said parts against lateral displacement with respect to the rail. 100

4. A shoe for a friction car stop adapted to be slidably mounted on a rail and comprising two wheel carrying parts that are spaced apart so as to expose between them a section of the wheel engaging surface of the rail, the first of said parts including a wheel obstructing portion and the second constituting a pull-back, means disposed laterally of the rail for tying said parts together, lugs depending from the first of said parts on opposite sides of the ball of the rail and terminating short of the underside thereof, and lugs depending from the second of said parts on opposite sides of the rail and extending underneath the ball thereof. 115

5. A shoe for a friction car stop adapted 120

4
to be slidably mounted on a rail, said shoe consisting of an integral casting and comprising two wheel carrying parts that are spaced apart so as to expose between them 5 a section of the wheel engaging surface of the rail, the first of said parts including a wheel obstructing portion and the second constituting a pull-back having a portion wherewith a car wheel is adapted to engage 10 for returning the stop to normal position, means disposed laterally of the rail for tying said parts together, and lugs depending from said parts alongside the ball of the rail, the rail engaging surfaces of the wheel carrying parts being comparatively soft, while the aforesaid wheel engaging portion of the pull-back is relatively hard.

6. In combination with a track and a bumper situated between the opposed rails of 20 the track and having structural members connected to the webs of said rails, a friction car stop comprising a shoe slidably upon one of said rails and including means co-operating with the ball of the rail to prevent 25 lateral displacement of the shoe, said means being designed to escape the connection between the rail and the structural member of the bumper, as and for the purpose specified.

30 7. In combination with a track and a bumper situated between the opposed rails of the track and having structural members connected to the webs of said rails, a friction car stop comprising opposed shoes slidable upon said rails, each shoe incorporating lugs depending on opposite sides of the balls of the rails, the ones located at the ends of the 35 shoes nearest the bumper terminating short of the under plane of the balls of the rails 40 thereby to avoid interference with the connections between the rails and the structural members of the bumper.

8. In combination with a track and a bumper situated between the opposed rails there- 45 of and involving structural members ex- tending along the inner sides of the rails and connected thereto, a friction car stop comprising shoes that are slidably mounted upon the opposed rails of the track, each of 50 said shoes consisting of a wheel obstructing part and a pull-back that are spaced apart to expose between them a section of the wheel bearing surface of the rail, the shoes incorporating lugs which depend on opposite 55 sides of the balls of the rails, certain of said lugs which are located at the ends of the shoes nearest the bumper being relatively short to avoid engagement with the connec-

tions between the aforesaid structural mem- 60 bers of the bumper and the rails.

9. In a friction car stop, a shoe that is adapted to be slidably mounted on a rail and comprising a wheel obstructing portion and a pull-back that are spaced apart so as to expose between them a section of the 65 wheel engaging surface of the rail, the wheel obstructing portion being adapted to be engaged by a wheel of a car when the car is moving in one direction and the pull-back being adapted to be engaged by a wheel 70 when the car is moving in the opposite direction, and means through which the shoe may be maintained in such relation to the wheel that the pull-back is held out of contact therewith when the car is moving in the 75 last mentioned direction.

10. In a car stop of the character set forth, a friction shoe slidably mounted upon the rail of a track and comprising a wheel ob- 80 structing part and a pull-back spaced from said part so as to expose between them a section of the wheel engaging surface of the rail, the wheel obstructing portion being adapted to be engaged by a wheel of a car when the car is moving in one direction 85 while the pull-back is adapted to be engaged by the wheel when the car is moving in the opposite direction, and means for shifting the shoe with respect to the car so as to maintain the pull-back out of contact with 90 said wheel during the movement of the car in the last mentioned direction.

11. A friction car stop comprising a pair of opposed shoes that are adapted to be slidably mounted upon the rails of a track, each shoe including a wheel obstructing portion at its forward end and a pull-back at its rearward end, said portion and the pull-back being spaced apart so as to expose between them a section of the wheel engaging sur- 100 face of the rail, the wheel obstructing portions of the shoes being adapted to be engaged by wheels of a car when the car is moving in one direction and the pull-backs being adapted to be engaged by said wheels when the car is moving in the opposite direction, and rigging for connecting the forward end of the car stop to the axle of said wheels and through which the car stop may be shifted so as to maintain the pull-backs out of engagement with said wheels when the car is moving in the last mentioned direction. 110

In testimony whereof, I hereunto affix my signature.

RUPERT BREYLEY.
